UNITED STATES PATENT OFFICE.

RALEIGH B. BUZZAIRD, OF SOUTH ORANGE, NEW JERSEY, ASSIGNOR TO PARLOC SERV-
ICE CORPORATION, OF NEW YORK, N. Y., A CORPORATION OF NEW YORK.

COIN-CONTROLLED LOCK.

Application filed August 11, 1921. Serial No. 491,609.

This invention relates generally to coin-controlled locks and more particularly to that well known class of locks adapted for use on doors of lockers or other compartments in railway stations, bath houses, club houses, etc. for the temporary storage of parcels or valuables.

The general object of the invention is to provide a lock which is as nearly "fool-proof" as can be expected and yet simple and cheap.

A particular object is a lock provided with means for preventing the entrance of a coin into the slot while the lock is in service.

Another special object is a lock provided with means for avoiding the loss of the coin before the lock is made effective.

The nature of the locking mechanism will appear fully from the description and the accompanying drawings forming a part of the specification.

In the drawings—

Fig. 1 is a front elevation of a locker showing the location of the lock;

Fig. 2 is a front elevation of the lock on a larger scale;

Figs. 3 and 4 are rear views of the locking mechanism showing the lock in inoperative and operative condition respectively;

Fig. 5 is a side elevation of the lock;

Fig. 6 is a front elevation of the locking mechanism, the front plate or escutcheon being removed;

Fig. 7 is a plan view of the lock;

Fig. 8 is a perspective view of a detail instrumental in closing the coin entrance;

Fig. 9 is a plan view of a detail arrangement;

Fig. 10 is a section on line 10—10 in Fig. 9;

Figs. 11 and 12 are perspective views of details shown in Figs. 9 and 10; and

Fig. 13 is a plan view of the main frame part shown in Figs. 9 and 10.

In Fig. 1 the lock is shown as applied to the locker frame 1, the door 2 being provided with a knob 3 of special construction as will be pointed out later on.

The front plate 4 has a coin entrance 5, an opening for exposing the key-slot end of the key cylinder 6 and an opening for exposing the indicia of Veeder meter 7 generally known in the art.

The arrangement of the locking mecha-

nism proper is best shown in Figs. 3, 4 55 and 6.

On the rear face of the front plate 4 is slidably mounted the lock bolt 8 by means of headed studs 9 and 10 projecting from the plate 4 and passing through slots 11. 60 The bolt has near its front end, a depending arm 12 and near its rear end a depending part shown for purposes of illustration as a spring 13.

To the rear wall of the plate 4 is also secured a coin chute 14 in alignment with the coin slot 5, the attachment being made by means of a flange 15 forming part of the chute structure and screws or rivets 16 extending through the flange into the front plate. As clearly shown in Fig. 8 a part of the chute structure is cut away to afford a slide way for a bolt 17. This bolt has a portion 17^a extending upwardly and adapted to project beyond the upper edge of the 75 chute, and a portion 17^b extending laterally to one side face of the chute structure. The portion 17^b has a recess 18 open at its edge for a purpose to be referred to later on. It may be mentioned here that the part of the 80 portion 17^b above the recess 18 in the position shown in Fig. 8 prevents a coin from entering the chute 14 and that the coin may freely enter when the bolt is moved downwardly a small distance. When the bolt is 85 in its uppermost position, the portion 17^a projects slightly from the upper surface of the chute structure.

Between the chute structure and the depending arm 12 on the lock bolt 8 is disposed 90 a spring 19 which tends to move the lock bolt into locking position indicated in Fig. 4. The outward movement of the locking bolt 8 is limited by the arm 12 abutting against the flange 20 bent back from the 95 front plate.

Mounted for sliding movement along the flange 20 is a detent 21 to which is connected the lower end of a spring 22 the upper end of which is connected to a stationary part, 100 for instance to the stud 10 as indicated. The stud 10 is for this purpose provided with an extension 23 so that the spring 22 operates free of the locking bolt 8, arm 12 and spring 19. The detent 21 has an inwardly extending lip 24 adapted to bear against the arm 12 to hold the lock bolt 8 in inoperative position as shown in Fig. 3. 105

When the detent 21 is pulled downwardly below the lower end of arm 12, spring 19 will force the lock bolt 8 to locking position. The downward movement of the detent 21 must be effected against the tension of spring 22. When the lock bolt is completely retracted from locking position, the detent 21 is forced upwardly again by spring 22 to the position shown in Fig. 3 locking the locking bolt 8.

In the space between the arm 12, the detent 21, the spring 19 and the chute structure 14 is disposed the tubular casing 25 containing the key cylinder 6. The casing 25 is attached to the rear side of the front plate 4 by means of a bracket 26 and screws or rivets 27.

The key cylinder 6 carries three angularly spaced fingers or cams 28, 29 and 30. The cam 28 takes into a recess 31 in the detent 21 while the cam 30 engages the recess 18 in the portion 17^b of the slide bolt 17. The cam 29 engages parts to be presently described.

Below the chute structure 14 and the key cylinder is mounted on the rear face of the front plate 4 a mechanism which constitutes one of the novel features of the invention. This mechanism includes a stationary frame 32 shown in plan view in Fig. 13. This frame is attached to the front plate 4 by means of screws or rivets 33 and affords a slideway for the coin receiver 34 shown in Fig. 12 and also a slideway for a plate 35 the function of which will be more fully pointed out.

As seen from Fig. 13, the upper surface 32^a of the frame 32 constitutes essentially a table for the plate 35. This table has a recess 36 and a recess 37. The recess 36 is large enough to allow the detent 21 to pass downwardly when the plate 35 is moved to the left in Fig. 10, a distance equal to the width of the recess 36. The recess 37 has the purpose to allow the cam 29 to angularly move to the position shown in Fig. 3.

The coin receiver 34 has a coin pocket 38 substantially of the width of the coin chute 14. When the receiver is in its extreme position to the right as shown in Fig. 3, the coin pocket 38 is directly below the chute 14. A coin dropped into the slot 5 can thus drop clear into the pocket 38. Adjacent the coin pocket 38 the coin receiver has a table 39 substantially flush with the upper edge of the coin pocket 38. For all positions of the coin receiver except its extreme position to the right indicated in Fig. 3 the coin will drop upon this table 39 and be held there until the receiver is moved to its extreme position to the right above referred to. On the inner surface of the wall 40 of the receiver contacting with the rear face of the front plate 4 are provided two pins or other suitable projections 41 and 42 be-

tween which is received the finger 29 as clearly indicated in Fig. 6.

The finger 29 will thus cause movement of the receiver 34 to either of the extreme positions indicated in Figs. 3 and 4 respectively.

The frame 32 has also a lower table or platform 43 over which the coin pocket 38 slides. This table 43 forms a bottom for the coin pocket and thus holds the coin therein until the receiver is moved to its extreme position to the left as indicated in Fig. 4. Just when this extreme left position is reached the coin pocket is free of the table 43 and the coin can drop out into a chute leading to the main receiver or collector.

The plate 35 has a longitudinal slot 44 and a transverse aperture 45. The slot 44 has the purpose to allow the cam 29 to angularly move independently of the plate 35. The transverse opening 45 allows the coin to drop upon the table 39 and rest thereon during relative movement between the receiver 34 and the plate 35.

The plate 35 is provided upon its bottom surface with a pin or other projection 46 adapted to bear against the free edge of table 39. It is thus clear that coin receiver 34 may slide to the left from the position indicated in Fig. 10 while the plate 35 remains at rest. However, when the receiver 34 is moved toward the right from the position of the parts indicated in Fig. 4, the table 39 will strike against the pin 46 and take the plate 35 along to the right.

At its front edge the plate 35 has a depending lug 47. The plate 35 and the coin receiver 34 are so related that in their extreme position toward the right as shown in Figs. 9 and 10, the lug 47 is in alignment with the outer wall of the coin pocket. The depth of the coin pocket is such that the coin 38^a will slightly project above its upper edge as shown in Fig. 3. When, with the coin in position in the pocket 38, the cam 29 is turned to the left in Figs. 9 and 10 or in Fig. 3, the coin will bear against the lug 47 and take the plate 35 to the left. The movement of the receiver 34 is limited toward the left in Fig. 3 by means of a pin 48, the extreme position being shown in Fig. 4 and also, as seen from the opposite side in Fig. 6.

The plate 35, as previously stated, slides upon the table 32^a. It bears at one edge against the rear surface of the front plate 4, and at the other edge against the flange 49 and is held in sliding contact with the table by means of a spring plate 50 attached to the frame 32 by means of a screw 51. It is understood, however, that the holding means may be integral with the frame 32.

The shaft of the Veeder meter 7 is connected by means of a link 52 with the detent 21. The link 52 is preferably a piece of wire

terminating in pintle portions 52^a and 52^b respectively. The portion 52^a extends loosely through a perforation in the meter crank 53 and the pintle portion 52^b extends into 5 a bore in the detent 21. As clearly indicated the length of the portion 52^b is such that the link portion 52 bears against the tumbler case 26^a and holds the detent in sliding contact with the side flange 20. The link wire 10 comprises two parallel portions offset relatively to each other.

By this arrangement the lower portion remains in contact with the tumbler casting 26^a and avoids interference with the 15 spring 22.

As appears clearly from Figs. 3 and 4, the upper end of the detent 21 or the lower end of the arm 12 or preferably both are slightly beveled for a purpose to be more 20 fully explained.

It should be noted that the key can be taken out only when the cylinder 6 is at the shedding point, as is well understood. This position is indicated in Figs. 4 and 25 6. This position can be obtained only after the coin is dropped and the locking bolt snapped to locking position. While the bolt 8 is in retracted position and held in that position by the detent 21, the detent 21 30 will prevent the turning of the cylinder 6 to shedding position because the plate 35 prevents downward movement of the detent. The effect of the arrangement is that after a person has unlocked the lock, the 35 key can not be withdrawn and remains in position for the next user.

The operation is as follows:

Assume that a person wants to use the locker. According to the printed instructions furnished for each locker, he first 40 deposits a coin in the coin-slot 5. The coin pocket being normally directly below the chute 14, the coin falls through the chute 14 and into the coin pocket 38.

The key is now turned in counter-clockwise direction or to the left. By doing this, the key 45 is turned in counter-clockwise direction or to the left. By doing this, the cam 29 will bear against pin 42 and move the coin receiver 34 to the left in Fig. 3 or to the right in Fig. 6 until it reaches its limiting position indicated in Fig. 4. The coin bears on the lug 47 as previously mentioned and thus takes the plate 35 with it.

During the turning movement of the key 55 55 the cam 28 bears against the lower shoulder defined by recess 31 and moves the detent 21 downwardly against the tension of spring 22.

During the turning movement of the key 60 60 the cam 30 bears against upper shoulder defined by the recess 18 and moves the bolt 17 upwardly.

When the key is in its normal position before operating, indicated in Fig. 3, the 65 lower end of detent 21 is an appreciable dis-

tance above the plate 35. The key can thus be turned an appreciable angle before the detent strikes against the plate 35.

At the same time the cam 30 is still in contact with the lower shoulder defined by 70 recess 18 and the bolt 17 is in its lower position. The key can thus be turned an appreciable angle before the cam 30 strikes against the upper shoulder of the bolt 17 and begins to move it upwardly.

On the other hand, the cam 29, almost immediately after the turning movement of the key has begun, will strike against pin 42 and move the coin receiver and the plate 35 through the coin to the left in Fig. 3 80 and the right in Fig. 6. The plate 35 is thus moved a distance equal to the width of the recess 36 before the cam 28 operates to move the detent 21 downwardly below the upper plane of the plate 35.

The first part of the turning movement of the key thus serves the purpose to clear away the plate 35 by means of the coin while the subsequent movement causes the downward withdrawal of the detent 21 and the 90 upward movement of the bolt 17.

As soon as the upper edge of the detent 21 passes by the end of arm 12, the spring 19 projects the locking bolt 8 into locking 95 position. The arm 12 then holds the detent 21 against upward movement. The projecting portion 17^a of the bolt 17 then intercepting the path of movement of the spring 13 prevents unauthorized unlocking of the lock.

At the same time the portion 17^b of the 100 bolt 17 has been moved upward and thereby closes a part of the entrance into the coin chute with the result that no additional coin can be dropped after the key is withdrawn. The key is now in shedding position and can be withdrawn.

To open the locker, the key is inserted and turned to the right. By this movement the bolt 17 is drawn downwardly by the cam 30 and the projecting portion 17^a of 110 the bolt 17 thus is moved out of the path of the spring 13. At the same time the coin receiver 34 and the plate 35 are moved to the right in Fig. 4.

To retract the locking bolt 8, I preferably 115 use a mechanism shown in detail in Fig. 6 and to be more fully described later on.

When the locking bolt 8 is approaching its extreme unlocking position the detent 21 120 is free to pass by the arm 12 and snaps into the space between the arm 12 and the side flange 20 due to the action of spring 22 and prevents the operation of the lock until another coin is dropped into the slot.

When the detent 21 is projected upwardly by the spring 22, it presses against cam 28 and takes it along, thereby imparting rotary movement to the cylinder 6. The cylinder 6, in turn, through cam 130

29 acts against pin 42 and retracts shelf 39 which strikes pin 46 of plate 35 bringing it back to its position where it obstructs the downward movement of the detent 21 and thus locks it in bolt-locking position. At the same time the coin pocket 38 has been re-aligned with the coin-chute 14 in normal position for a new operation with another coin.

10 The door can now be opened and the checked articles can be removed.

One very material feature of the invention is the beveling of the detent and the arm 12 or either of them as previously briefly 15 mentioned. If the bevel or bevels were not provided, the cam 28 would remain in contact with the detent 21 and the spring 22 would exert pressure upon the cam 28 and through the cam 28 upon the cylinder 6 20 which would cause a binding action between the inside lock tumblers and the cylinder after the key is withdrawn. The result would be that the key must be forced into position and after being placed again in 25 position could not be turned without force to the right and the bolt 17 could not be moved to inoperative position. The mechanism in the cylinder 6 would wear out in a relatively short time.

30 By means of the bevel arrangement the end of the arm 12 will ride over the bevel on detent 21 or the bevel on the arm 12 will act as a cam or both bevels will cooperate to move the detent downwardly during the 35 movement of the locking bolt to locking position. The bevel or bevels may be so dimensioned that the detent is moved about $\frac{1}{32}$ inch or even less. This movement is sufficient to clear the cam 28 so that the spring 40 22 can not act upon it.

Another feature of considerable importance is the mechanism for retracting the locking bolt. On the door is mounted a bolt or pin 56 and a knob 3. The knob 3 carries 45 a cam, preferably a cam having two cam faces 57 and the pin 56 has its rear end 56a within the sphere of action of the cam. The knob can be completely rotated only to the left or in counter-clock-wise direction as appears clearly from Fig. 6. When the knob is turned the cam will bear against the end 56a of the pin 56 and force it to the right against the arm 12 causing the bolt 8 to move 50 to unlocking position. The arrangement is such that when the bolt 8 is completely retracted the cam will pass over the end of the pin 56 and the latter will snap back under the force of the spring 58.

60 The arrangement just described has a double aspect. The primary and more important one is the protective feature. The pin 56 has been intentionally located to bear against arm 12 or in general against any other part of the bolt positioned rearwardly 65 of the front end of the bolt 8 so that in case

an unauthorized person in an attempt to retract the bolt should succeed in forcing the spring 13 over the projecting part of the bolt 17, he cannot open the door. It should be noted that while the key is withdrawn the cylinder 6 is locked and the cam 28 holds the detent in inoperative position although the bolt 8 may be in retracted position. If now in the assumed case the person should retract the bolt 8 to its inoperative position, the pin 56 will at the same time extend into the lock and is just as effective in locking the door as the bolt 8. It is obvious that there can be no position of either the bolt 8 or of the pin 56 in which the lock is ineffective when the key is out. In fact for all positions of the bolt 8 except the completely retracted position after the key has been inserted both the bolt 8 and the pin 56 constitute a barrier against opening of the door.

85 The second aspect has to do merely with the peculiar habits of users. It has been found from experience that even intelligent persons do not use good judgment in the use of locks of the character involved. They almost invariably turn the knob and expect the door to open. If it should not open they pull impatiently and do all sorts of irrational things rather than to use judgment in locating the difficulty. The door can be 90 opened only if the bolt 8 is retracted to its limit of movement. The pin 56 must be moved forwardly to the limit of its movement and then retracted. As simple as this 95 operation is, people would have no end of difficulty with the lock.

100 The arrangement shown takes into account the peculiar attitude of the users. A user invariably wiggles the knob in an effort to turn it. The knob can be turned only in one direction. When it is turned in that direction the pin is moved far enough to move the bolt 8 to inoperative position and the detent 21 snaps up behind arm 12 and holds the bolt 8 retracted. As soon as this is 105 accomplished the pin 56 snaps back with a click. This snapping back is so quick that the user has no time to pull. When he hears the click he takes it for granted that the 110 door is open. While the door is actually open, the clicking has nothing to do with it. However, it invariably operates to give to the user the signal to pull on the knob to 115 open the door.

120 While I have described this arrangement with a bolt locked in operative position, its use is of broader scope. In fact it is more useful in cases where the bolt 17 or its equivalent is omitted and the latch bolt may be retracted at will.

125 In the foregoing I have described what I at present consider as the preferred form of the invention and I am fully aware that various changes may be made within the scope 130 of the invention.

I claim:—

1. In a lock, the combination of a bolt, a 50
detent for holding the bolt in inoperative
position, means for locking the detent in
holding position, and coin-controlled key-
operated means for making the locking
means inoperative and for withdrawing the
detent from holding position.

2. In a lock, the combination of a bolt, 10
spring means tending to move the bolt in
one direction, a detent for holding the bolt
in inoperative position, means for locking
the detent in holding position and coin-
controlled key-operated means for making
15 the locking means inoperative and for with-
drawing the detent from holding position.

3. In a lock, the combination of a bolt, 20
spring means tending to move the bolt to
locking position, a detent for holding the
bolt in inoperative position, means for lock-
ing the detent in holding position and coin-
controlled key-operated means for making
25 the locking means inoperative and for with-
drawing the detent from holding position.

25. 4. Device according to claim 1 including
spring means tending to move the detent to
holding position.

30. 5. Device according to claim 1 including
means on the bolt for retaining the detent in
inoperative position when the bolt is shot.

35. 6. In a lock, the combination with a bolt,
a detent for holding the bolt in inoperative
position, means for locking the detent in
holding position, key-operated means for
50 withdrawing the detent from holding posi-
tion and coin-control means connected with
the key-operated means operative to make
the latter effective when a coin is inserted,
the arrangement being such that the key can
40 be withdrawn when the bolt is moved to
locking position and that the key can not be
withdrawn so long as the bolt is in inoper-
ative position.

45. 7. Device according to claim 6 including
means tending to move the bolt to locking
position.

50. 8. Device according to claim 6 including
means tending to move the detent to holding
position.

55. 9. Device according to claim 6 including
means tending to move the bolt to locking
position and means tending to move the
detent to holding position.

60. 10. In a lock, the combination of a bolt
and key-operated means including a coin-
controlled mechanism for controlling the
bolt, the said means including an element
operative, when the bolt is moved to locking
65. position, to block the bolt and close the coin
entrance.

11. In a lock, the combination of a spring-
pressed bolt, and key-operated means in-
cluding a coin-controlled mechanism for
shooting the bolt, the said means including
65. an element operative, when the bolt is in

locking position, to lock the latter and close
the coin entrance.

12. In a lock having a coin-entrance, the
combination of a spring-pressed bolt, a 70
spring-pressed detent for holding the bolt in
inoperative position, an element for locking
the bolt in locking position and for closing
the coin entrance, and key-operated means
including a coin-controlled mechanism for
75 withdrawing the detent from holding posi-
tion and for actuating said element.

13. In a lock, the combination of a spring-
pressed bolt, a spring-pressed detent for
holding the bolt in inoperative position, and
means for withdrawing the detent from 80
holding position, said means including a
movable member for locking the detent in
holding position, a coin receiver movable in-
dependently of the said member and means
cooperating with a coin in the coin receiver
85 for moving the member out of locking posi-
tion when the coin receiver is moved in one
direction.

14. In a lock, a spring-pressed bolt, a 90
spring pressed detent for holding the bolt
in inoperative position, a member for lock-
ing the detent in holding position, a coin re-
ceiver, means for slidably supporting the
said member and the coin receiver inde-
pendently of one another, means on the said
95 member cooperating with a coin in the coin
receiver to move the member out of locking
position when the coin receiver is moved and
key operated means for moving the coin re-
ceiver and the detent. 100

15. In a lock, a spring-pressed bolt, a
spring-pressed detent for holding the bolt in
inoperative position, a coin receiver, a plate
above the coin receiver positioned to lock
the detent in holding position, means for
105 slidably supporting the coin receiver and the
plate independently of one another and a lug
on the plate cooperating with a coin in the
receiver to cause movement of the plate out
of locking position when the coin receiver is
110 moved, and key-operated means for moving
the coin receiver and the detent.

16. In a lock, a spring pressed bolt, a
spring pressed detent for holding the bolt in
inoperative position, a plate for locking the
detent in holding position, a coin-receiver
having a coin pocket and a table adjacent
the upper edge of the pocket, the plate hav-
ing an opening substantially coextensive
with the table, means for slidably support-
ing the plate and the coin receiver inde-
pendently of one another, the plate being
disposed above the coin receiver, a lug on
the plate cooperating with a coin in the re-
ceiver to cause movement of the plate out of
locking position when the coin receiver is
moved in one direction, and key-operated
means for moving the detent and the coin
receiver. 125

17. In a lock, a spring-pressed bolt, a 130

spring-pressed detent for holding the bolt in inoperative position, means for locking the detent in holding position, and key-operated coin-controlled means for withdrawing the said locking means and for withdrawing the detent from holding position.

18. In a lock, having a coin entrance, a spring-pressed bolt, a spring-pressed detent for holding the bolt in inoperative position,

means for locking the detent in holding position, an element for locking the bolt in operative position and for closing the coin entrance and key-operated coin-controlled means for withdrawing the said locking means, for withdrawing the detent and for actuating the said element.

In testimony whereof, I affix my signature.
RALEIGH B. BUZZAIRD.
